UNITED STATES PATENT OFFICE.

HARRY EARL SMITH, OF TOPEKA, KANSAS.

CARBON-STICK HOLDER.

1,245,164.

Specification of Letters Patent. Patented Nov. 6, 1917.

Application filed February 9, 1917. Serial No. 147,644.

To all whom it may concern:

Be it known that I, HARRY EARL SMITH, a citizen of the United States, residing at Topeka, in the county of Shawnee and State 5 of Kansas, have invented a new and useful Carbon-Stick Holder, of which the following is a specification.

The present invention relates to a device adapted for use in the booth occupied by 10 the operator of a motion picture machine, and aims to provide a device having a rack for holding a quantity of unused carbon sticks whereby they may be readily removed and applied to the motion picture machine, 15 the device also embodying a receptacle for receiving the burnt or used sticks of carbon after they are taken from the machine, and whereby the used sticks or fragments will be confined within the receptacle to prevent 20 danger of conflagration, and so that the receptacle may be removed and dumped from time to time.

The invention embodies a stand adapted 25 for holding the unused sticks of carbon, and a removable receptacle supported by the stand and of peculiar construction for receiving the used sticks of carbon, and to allow its contents to be discharged when the receptacle is removed from the stand.

30 The invention also resides in certain novel features of construction, which enhance the utility of the device, and it is also within the scope of the invention to provide a device having the features above noted, and which 35 at the same time, is comparatively simple, light, non-encumbering and inexpensive in construction.

A further object of the invention is the provision of a carbon stick holder of the 40 character specified which will be especially useful in connection with a motion picture machine, although the device may be used for other purposes as well, the device being thoroughly practical and efficient in use.

45 With the foregoing and other objects in view which will appear as the description proceeds, the invention resides in the combination and arrangement of parts and in the details of construction hereinafter 50 described and claimed, it being understood that changes in the precise embodiment of

the invention herein disclosed can be made within the scope of what is claimed, without departing from the spirit of the invention.

55

The invention is illustrated in the accompanying drawing, wherein:—

Figure 1 is a perspective view of the improved carbon stick holder.

Fig. 2 is an enlarged vertical section 60 through the receptacle and upper end portion of the stand.

Fig. 3 is a plan view of the device.

In carrying out the invention, the device embodies a stand 1 supporting a receptacle 2.

65 The stand 1 embodies four corner legs 3, preferably formed from angle iron, and lower and upper shelves 4 and 5, respectively, are secured to the legs 3. Horizontal angle iron members 6 are terminally secured to the upper ends of the legs 3 and provide means for receiving the receptacle 2. The unused carbon sticks may be piled upon 70 the lower shelf 4 between the opposite legs 3, and the tools or implements may be placed upon the shelf 5 when desired, in order that 75 they are readily accessible.

The receptacle 2 which is preferably constructed of sheet metal embodies a bottom 7 80 adapted to seat within the angle iron members 6 at the upper end of the stand 1, sides 8, back 9 and front 10. The front 10 of the receptacle 2 is provided with a lower opening 11 extending completely between 85 the sides 8, and the receptacle 2 has an inclined false bottom or chute 12 therein extending upwardly from the lower edge of the opening 11 to the back 9 of the receptacle. The side edges of the false bottom or 90 chute 12 are secured to the sides 8 of the receptacle.

95 Upright angle iron members 13 have certain of their flanges secured to the sides 8 of the receptacle adjacent the front of said receptacle, the angle iron members 13 extending around the front corners of the receptacle and having their other flanges overlapping but spaced from the front of the receptacle. The members 13 thus provide 100 guides at the side edges of the opening 11 and extending above said opening. A sheet

- metal door 14 is slidable upon the exterior of the front 10 of the receptacle and its side edges are received slidably by the angle iron guide members 13, whereby the door 14 is guided for vertical movement to and from the opening 11. The upper edge of the door 14 has an outturned flange 15 whereby the door may be readily opened and closed by the hand, when the door is released.
- 10 It is preferable to secure a spring catch or latch 16 to the outer side of the door 14 in order to normally hold the door closed, the latch 16 depending and having an in-turned finger 17 at its lower or free end 15 which is engageable under the bottom 7 of the receptacle. The free portion of the latch 16 seats within the front angle iron member 6 when the receptacle 2 is placed upon the stand, which will hold the latch 16 in engagement with the bottom of the receptacle 20 to prevent the door 14 from being accidentally opened while the receptacle 2 is in place upon the stand. When the receptacle 2 is lifted off of the stand, the latch 16 may 25 be readily sprung outwardly to release the door 14 and to allow the door to be readily raised or opened. This latch 16, however, need not be employed in all cases, but is of advantage for the reasons above 30 pointed out.

An inclined plate 18 has its side edges secured to the sides 8 of the receptacle and has its upper end secured to the front 10 of the receptacle, the lower end of the plate 18 35 being spaced from the back of the receptacle and said plate being spaced below the upper edges of the walls of the receptacle. An inclined plate 19 has its side edges secured to the sides of the receptacle and has 40 its upper end secured to the back 9 of the receptacle. The lower end of the plate 19 terminates short of the plate 18 and is spaced therefrom, and the plate 19 is located opposite the plate 18 and is disposed 45 below the upper edges of the walls of the receptacle. The lower end portion of the plate 19 is bent back approximately parallel with the lower end portion of the plate 18, as at 20, and provides an outlet spout 21 50 for the hopper which is formed by the plates 18 and 19 with the upper edge portions of the walls of the receptacle. The spout 21 overhangs the chute 12, and a flap valve 22 55 is hinged to the end portion 20 and normally swings against the lower end of the plate 18 to close the spout 21.

In use, the unused carbon sticks are piled within the rack formed by the stand 1, and when the burnt or used sticks are removed 60 from the machine, they are dropped in the upper hopper of the receptacle 2, it being noted that the sticks when removed from the machine are generally hot and are liable to start a conflagration if they are not pro-

tected. With the present device, the used sticks in being dropped into the hopper will pass downwardly through the spout 21 into the receptacle 2 to be protected therein, the valve 22 opening when the sticks pass downwardly out of the spout 21. The valve 22 70 closes by gravity to prevent the fumes or heated gases from rising out through the spout 21. The door 14, as above indicated, is normally closed, and the inclined chute 12 will cause the contents of the receptacle 75 2 to run downwardly and bear against the door 14.

The contents of the receptacle may be dumped or discharged from time to time, and this is conveniently done by lifting the 80 receptacle off of the stand, in which event the door 14 can be opened to dump the contents of the receptacle into the waste or refuse can. If the latch 16 is eliminated, the door 14 can be opened without removing 85 the receptacle 2, in order that the contents of the receptacle may be discharged without removing the receptacle from the stand.

The present structure is constructed entirely of metal, mostly sheet metal, and is 90 fire proof. The structure is also comparatively simple and not cumbersome, but on the other hand is light and portable and is pleasing or attractive in appearance.

The device may not only be used in motion picture booths, but may be utilized for other purposes as well.

Having thus described the invention, what is claimed as new is:—

1. In a device of the character described, 100 a stand, a receptacle supported removably thereby, one wall of the receptacle having an outlet opening, a door for normally closing said opening, and a latch for holding the door closed engaging the stand to prevent the releasing of the latch unless the receptacle is removed therefrom.

2. In a device of the character described, 110 a stand, a receptacle supported removably thereby, one wall of the receptacle having an outlet opening, a door for normally closing said opening, a latch carried by the door engageable with the receptacle for holding the door closed and normally engaged with the stand to prevent the releasing of the 115 latch unless the receptacle is removed from the stand.

3. In a device of the character described, 120 a stand, a receptacle supported thereby, one wall of the receptacle having an outlet opening, a vertically slidable door carried by the receptacle for normally closing said opening, and a latch carried by the door and engageable under the receptacle, and engaging the stand when the receptacle is supported thereby.

4. In a device of the character described, 125 a stand, having upper angle iron members,

a receptacle removably seated in said members, one wall of the receptacle having an outlet opening, a vertically movable door carried by the receptacle for normally closing said opening, and a latch carried by the door and having a portion normally engaging under the bottom of the receptacle and seating in one of said members.

In testimony that I claim the foregoing as my own, I have hereto affixed my signature in the presence of two witnesses.

HARRY EARL SMITH.
